ADHERED STRIP OF FULL-HEADED NAILS
Arthur Langas and Melvyn J. Howell, Chicago, Ill., as
signors to Signode Corporation, a corporation of Dela-
ware

Filed Dec. 14, 1964, Ser. No. 418,114
1 Claim. (Cl. 206—56)

This invention relates to adhered strips of nails and, particularly, to a strip of full-headed or "common" nails for use in magazines of rapid-acting fastener driving tools.

With the advent of fast-acting fastener driving tools, it became necessary to have nails available in strip form for use in the magazines of such tools. Nails assembled in strip form can be conveniently handled and the time necessary to load the nail magazines is reduced to the bare minimum. With nails available in this form, an operator can load the tool magazine in very short order. It is only recently that full-headed nails like the so-called "common" nail have been available in strip form. Such nails are presently being assembled by a variety of methods, each of which has required the providing of substantial quantities of material between the nail shanks, or as a backing for the row of nails. For example, one such method being used consists of injecting substantial quantities of plastic into the space between the nail shanks, and other includes the use of a paper backing for the nails to which the nails are secured by a string, or the like. It can be appreciated that when any of these forms of nail strips are used in fastener driving tools, the material used to retain the nails in strip form would be driven with the nail and would tend to clog the tool during the driving action. Such clogging action would seriously affect the speed at which the tool could be operated and thus would tend to seriously impair the efficiency thereof.

Other obvious disadvantages of these methods include the substantial expense involved in assembling the strip and the cost of the materials employed.

It is, of course, desirable that the nail strip be formed so that the nails are positively held in position, but, on the other hand, the strip must be sufficiently flexible to prevent the strip from fracturing in the event the strip is dropped or otherwise carelessly handled. It would also be advantageous if the materials retaining the nail in strip form be kept at a minimum, so as to prevent clogging of the tool during the driving action. Another advantage inherent in such an arrangement is that the area surrounding the work area will be kept free of such material.

In the case of a magazine designed to accommodate longitudinal strips of nails, the nails should be secured in an assembled position with sufficient strength to insure that the row of nails will remain in substantial alignment to enable the operator to quickly and easily load the magazine.

If the strips are to be used in magazines that are designed to receive nails in a spiral configuration, the strips must be sufficiently flexible to permit coiling of the nails without the strip fracturing or the nails separating from the strip. Such magazines are capable of holding a larger quantity of nails than one accommodating longitudinal strips.

In accordance with the present invention, there is provided in one embodiment thereof a longitudinally extending strip of common nails in which the nails are disposed in a stepped or "tiered" relationship to permit nesting of the nails to facilitate assembling the maximum number of nails within the minimum length. During the assembly process, the nails are first positioned by placing the head of one nail under the head of an adjacent nail

2

and into abutting relationship with the shank of the adjacent nail. The shanks of the nails are located parallel to each other. This placing of the nails is continued until a row of the desired length is formed. The nails in the strip are adhered together and maintained in the stepped relationship by a tape coated with an adhesive that secures the shanks to the tape. The tape is in tangential relationship with the nail shanks and extends parallel to a line interconnecting the nail heads. The tape is located on both sides of the nail row and the adhered strip so formed is resilient to permit limited flexing, but is sufficiently rigid to permit ready insertion into the magazine provided for same. This novel construction obviates the necessity of providing an adhesive or other bonding materials in the space between the adjacent nail shanks or the use of paper backing or spacers, as in the case with other nail strips currently on the market. The elimination of such materials is extremely important since it does away with the clogging and other problems that occur when they are present. In addition, the strip can be very easily manufactured since it merely requires the application of a tape and no separate application of an adhesive is required. The cost of such a strip over those currently available is substantially reduced since it uses a minimum amount of adhesive per unit length.

In the case of a nail strip to be used in a magazine designed to receive a spiral strip of nails, or one in a form other than a longitudinally extending strip as described above, the nail strip is assembled by disposing the nails in a parallel pattern with their heads in the same plane and in abutting relationship with the head of an adjacent nail and the shanks parallel. The nails are affixed into an adhered array by an adhesive-backed tape, which tape is disposed in tangential contact with one side of the row of nails. With only one side of the nails being interconnected in the fashion, the strip so formed can be wound into a spiral or other non-linear configuration. The flexibility of such a strip is obvious and such flexibility enables the strip to be formed in whatever pattern desired. It is seen that with this arrangement, there is still no material located between the shanks of adjacent nails other than the tape itself and thus this strip contains the same advantages discussed above with respect to the linear adhered strip. That is to say the likelihood of the tool being jammed during firing thereof by adhesive or paper is obviated, the cost of such a strip is minimized, and it can be manufactured without difficulty.

The other advantages and features of this invention will be seen from the following description taken in conjunction with the drawings, in which:

FIGURE 1 is an adhered strip of nails in which the nails are disposed in tiered relationship and are formed into an adhered array by a tape with an adhesive backing extending across the medial portions of the nail shanks;

FIGURE 2 is a cross-sectional view taken along the lines 2—2 of FIGURE 1;

FIGURE 3 is a view showing a strip of nails in which the heads are coplanar and the shanks are interconnected at their midsections by a single strip of adhesive tape;

FIGURE 4 is a view taken along lines 4—4 of FIGURE 3; and

FIGURE 5 is a view showing the nail strip of FIGURE 3 wound in a spiral pattern.

Referring first to FIGURES 1 and 2, there is shown an adhered strip of common nails 2 having full heads 4 and cylindrical shanks 6. The nails 2 are angularly disposed with the head 4 of one nail being located beneath the head 4 of the nail located on its right and in contact with the shank portion 6 of the adjacent nail. The space 7 between the overlapped heads can be varied depending on the con-

figuration the strip is to take. The shanks are spaced apart an amount equal to the width of the overlapping head portion as indicated at 8 on the drawings.

A typical strip configuration is one in which the nails form an angle of about 30° with the horizontal when they are mounted for firing in the magazine of a fastener driving tool. When located in the magazine, the head portion of the lowermost nail in the strip not covered by the adjacent nail is exposed to the nail driver, whereby the nail may be driven into the boards to be joined.

The nails are retained in the relationship shown in FIGURE 1 by tapes 9 coated on their underside with a heat-responsive adhesive 10. The tape strips 9 are mounted on both sides of the shanks 6 and in tangential contact therewith, as indicated at 11. The tape engages the medial portion of the shank 6 and extends in a direction parallel to a line joining the heads of the nails. One way of assembling the strip is to pressure-apply the tape to heated nails.

It can be appreciated that the nail strip so formed will have a limited amount of resiliency to prevent fracture in the event the strip is dropped, but will maintain the strip in its assembled form so it may be readily inserted into a magazine designed to receive same in proper position for firing.

It is to be noted that there is no plastic, or other materials, located between the shanks.

In the embodiment shown in FIGURES 3-5, the common nails 20 having full heads 22 and cylindrical shanks 24 are adhered into strip form by means of a single tape 26 having on its underside a heat-sensitive adhesive 28 which bonds the nails to the tape. The single tape 26 is in tangential contact with a medial portion of the shanks 24 and is disposed parallel to the plane in which the heads 22 are located. In this embodiment, the nail heads 22 are coplanar and are disposed in abutting relationship with an adjacent nail. When using a single tape, the nails may be formed into the spiral arrangement 30 shown in FIGURE 5 for insertion into a similarly designed magazine. In a strip of this type, the entire head area will be exposed to the driving blade when inserted into a fastener driving tool. The adhesive 28 contacts the shanks 24 as indicated at 25 and as such positively retains the nail in place relative to the tape 26.

It is also seen that here there is no adhesive or other material located between the shanks of the nails which would tend to bring about jamming when the nails are driven. The tape can be easily manufactured and requires a minimum amount of adhesive.

While two embodiments have been illustrated and described, it will be understood that changes could be made without departing from the spirit or scope of the invention. For example, while the nail heads as shown in FIGURE 1 are illustrated as being in contact with the shank of an adjacent nail, the heads may be spaced slightly apart since the nails are maintained in their relative

positions by the adhering means and do not depend on the contact between the head and adjacent shank. This is equally true with respect to FIGURE 3, wherein the nail heads may not contact an adjacent nail head. Furthermore, while a particular tape has been referred to, other tapes could be used consistent with the present invention.

It is, of course, intended to cover by the appended claim all such embodiments as fall within the true spirit and scope of the invention.

We claim:

An adhered strip of nails for a rapid-acting driving tool magazine, comprising a plurality of nails, each of said nails having a full head, a cylindrical shank connected to said full head, and a point formed at the end of said shank opposite the end connected to said head, said nails being disposed in stepped, contacting relationship with the head of one nail being located in overlapping relationship with the head of an adjacent nail, and said shanks being spaced apart from each other to define an open area between each of the adjacent shanks, said open area consisting only of air in order to minimize clogging problems; means for connecting said nails to form a strip, said connecting means comprising a first adhesive tape extending across a first portion of the shank of each adjacent nail in tangential contact therewith, leaving said open area void of material other than air, a second adhesive tape extending across a second portion of the shank of each adjacent nail in tangential contact therewith, leaving said open area void of material other than air, said first and second adhesive tapes each comprising a front portion and a backing portion including a head responsive adhesive to provide a connection between said tape and said nails when said tape is pressure applied to the nails while the nails are in a heated condition, said first and second adhesive tapes each extending across said shanks in a direction parallel to the line formed by the adjacent nail heads, said first and second adhesive tapes each being of a width that is less than the length of the nails to which it is connected, and said first and second adhesive tapes comprising the sole connecting means for said nails.
